UNITED STATES PATENT OFFICE.

JAMES W. VANMETER, OF SAN FRANCISCO, CALIFORNIA.

ORE STAMP-MILL.

1,353,097.

Specification of Letters Patent. Patented Sept. 14, 1920.

Application filed November 5, 1919. Serial No. 335,902.

To all whom it may concern:

Be it known that I, JAMES W. VANMETER, a citizen of the United States, residing at the city and county of San Francisco and 5 State of California, have invented certain new and useful Improvements in Ore Stamp-Mills, of which the following is a specification.

My invention relates to that class of ore-10 stamp mills in which the material is carried by a mortar and is crushed by receiving a violent blow, the resultant pulp being thus rendered favorable for the amalgamation of its precious particles with the quicksilver 15 in the mortar, and reduced to a condition, under the influence of repeated blows, to pass away from the mortar through its screen, to be delivered to the collecting tables.

20 In common practice in this type of stamp mill the mortar is stationary and the crushing blows are delivered by dropping heavy stamps upon the material in the mortar. I have found, however, that by reversing this 25 practice, so that the stamp is stationary and the mortar reciprocative, a mill of this general class may be produced having many constructive advantages in point of economy in manufacture, weight in transportation, 30 and capacity in operation, the last named advantage being due chiefly to a better amalgamation owing to the more complete crushing effect of the entire mass bodily thrown or carried or impacted against the 35 stamp by the moving mortar; and the more positive projection of the pulp against the mortar screens, and the consequent continuous cleansing effect of the splashed water tending to keep the screen mesh open, there- 40 by increasing the delivery capacity of the mill.

Furthermore, in connection with this reversal of movement of the crushing members, it is practicable to arrange for the 45 swinging outward from the frame, of all the operative parts of the mill to afford convenient access to them whenever necessary; and lastly, it is not only practicable, but decidedly advantageous to so construct the reciprocative mortar as to embody in itself 50 the prime-mover by which its reciprocation and functional blow are effected.

The object of my invention is, therefore, to realize in an ore-stamp-mill of what may 55 be termed the mortar and stamp type, these and other advantages, which I shall here-

inafter describe and demonstrate more in detail; and to this end my invention consists in the novel ore-stamp-mill which I shall now fully describe, by reference to the 60 accompanying drawings, in which

Figure 1 is a front elevation of my ore-stamp-mill.

Fig. 2 is a side-section of the same.

Fig. 3 is a vertical side sectional view of 65 the mill.

Fig. 4 is a sectional view of the fuel-feed pump.

Fig. 5 is a vertical front section of the mill.

Fig. 6 is an elevation of the mill showing 70 the mortar turned out from the frame.

Fig. 7 is a horizontal cross section taken at the base of the frame, showing said base 75 in plan.

Fig. 8 is a top plan view of the mill.

The frame comprises a base 1, a column 2 and an overhanging top 3. Bolts 4 through the base anchor the frame. The column 2 is 80 arcuate in cross section as seen in Fig. 7.

Through the overhang of the top 3 pass the vertical guides 5 one on each side. These extend down to and freely enter the base 1, as seen in Fig. 5. 6 is the mortar. It is mounted, for vertical reciprocative movement, upon the guides 5, and rests normally upon cushions or bumpers 7 in the base 1. 8 is a fixed stamp. It shoulders under the frame top 3 as shown clearly in Figs. 3 and 5, and is suspended therefrom by means of 90 a sleeve 9 to which it is secured, as, for example, screwing. The sleeve 9 passes through the top 3 and is headed thereon. Thus the stamp 8 is rigidly fixed, but may be readily disconnected from the frame by 95 unscrewing the suspending sleeve 9. The sleeve 9 has an axial bore 9' and the fixed stamp has an axial bore 8' alined with the bore of the sleeve Fig. 5. To the stamp is fitted the die 10 with a bore 10', and to the 100 upper end of the sleeve 9 is fitted the feed hopper 11.

The ore is supplied to the mortar 6 from the hopper 11, by passing down through the bores 9', 8' and 10'.

105 The mortar 6 is fitted with an annular shoe 12 and with a liner 13. The liner is held in position by means of the bevel or wedge shape of the shoe 12, as shown at 15.

Fitted to the mortar above the liner is the 110 screen 17. Outside of the screen the mortar is chambered at 18, said chamber having a

bottom inclining to one side as indicated by the dotted line in Fig. 3, and opening into a discharge passage 19 made in the mortar and leading down to and through its lower 5 end to the space thereunder, which said space communicates with an outlet 29 in the base 1, Figs. 3 and 7.

Fitted to the mortar at 21, and hanging down within the upper portion of the space 10 between the screen 17 and the stamp 8 is a funnel shaped guard 22 of relatively light metal, and in the annular space above this guard, lies an inverted funnel guard 23, encircling the stamp.

15 Before proceeding with the further description of the mill, it will be well, at this point to describe generally the operation of the parts thus far disclosed.

The ore and water are fed to the mortar 20 from the hopper 11, through the stamp 8, as heretofore mentioned. The mortar is forcibly driven upwardly, on its guides 5, and the ore it carries thus violently brought into contact with the fixed stamp 8. The 25 splash is thrown upwardly into the space around the stamp, and meeting the overlying funnel guard 22 is directed substantially at right angles outwardly against the screen 17. Such splash as may pass the 30 guard 22 is arrested by the inverted guard 23 and thereby prevented from issuing above to the detriment of the sliding surfaces of the mortar on its guides 5. The pulp passes through the screen 17 into the surrounding 35 chamber 18 and thence, falling through the passage 19, is delivered by the outlet 20 in the base.

To obtain access to the interior of the mill, the suspending sleeve 9 is unscrewed from 40 the stamp 8, which thereupon drops into the mortar. Then one of the vertical guides 5 is withdrawn from the mortar, and the latter, containing the stamp, is turned about the other guide 5 as an axis, to a position 45 away from and clear of the frame column 2 and overhanging top 3, and in this position is supported by inserting a pin 5' through the mortar into a socket 5" in the guide as shown in Fig. 5.

50 The means for operating the mortar will now be described, reference being made particularly to Figs. 3 and 5.

The mortar from its bottom upwardly to within a short distance of the base of its 55 shoe 12 is chambered out at 25 to form what is in effect the cylinder of an explosive engine, and in the mortar about this cylinder, top and sides, is a chamber 26 of a water cooling system, of which 27 and 28 are the 60 inlet and outlet respectively.

Resting upon but otherwise free of the frame base 1 is a piston 29 which fits within the mortar cylinder 25. The space between the top of the piston and the upper end of 65 the mortar cylinder constitutes the explosion

or combustion chamber 25', associated with which is the spark plug 30 of the ignition system, said plug being seated in a lateral opening 31 in the mortar, and having the circuit wires 32, extending to the operating 70 switch presently to be described.

The piston 29 has formed in its axis the valve chamber 33, the ends of which are closed by screw plugs 33'.

Within the chamber 33 is mounted for 75 longitudinal movement a piston valve 34 having three packed heads 35 separated by intervening necks 36.

Leading through the lower portion of the side of the piston, into the valve chamber 80 33 below the lower head of the piston 34 is an air passage 37, Fig. 3. Leading laterally into the piston and thence upwardly into its wall is a second air passage 38 which leads in the valve-chamber 33 above the upper head of the piston 34, Fig. 3.

Connected with the passage 37 is a hose 39, and connected with the passage 38 is a hose 40.

The control of the air through hose 39 and 90 passage 37 is as follows:—Seated in the base 1 is a valve shell 41, Fig. 3, with an inlet connection 42 from a source of compressed air, not shown, and an outlet connection 42' with the hose 39. A valve 43 controls the 95 communication between these two connections, in such manner that the entering compressed air normally holds the valve up to its seat and cuts off the communication. The valve 43 has a stem 44, which projects upwardly through the top of the shell and is adapted to be struck by the descending mortar, which has the effect of depressing the valve and opening the air connection to the hose 39. 100

The control of the air through the hose 40 and passage 38 is as follows:—Let into the upper portion of a vertical bore 45 Fig. 3 in the base of the mortar is a freely slidable weight 46, the upper movement of which 110 is limited by a bumper 47. In the lower portion of the bore 45 is fitted a plug 48. A connection 49 with a source of compressed air, not shown, passes upwardly through the plug 48 and opens into the bore between the top of the plug and the bottom of the weight 46. In the top of the plug is formed a port 50 from which leads a passage 51 to the hose 40. A valve 52 controls the port 50. This valve has a stem 53 projecting upwardly freely through the weight 46 and is provided with a collar 54 on its top, and said valve has also a stem 55 extending freely downwardly through the plug, and projecting sufficiently to contact with the base 1 when 120 the mortar descends. 125

56 is a drainage depression in the base 1 to take care of the oil waste from the piston.

57 is an air passage, leading from an air connection with a source of compressed air, 130

not shown. This passage leads through the wall of the piston 29 and enters the valve-chamber 33 through the port 58.

59 is another port in said valve chamber 5 with which an air passage 60 communicates, said passage leading upwardly through the piston 29 into the combustion chamber 25'.

61 is an outlet passage for the products of combustion.

10 62 is a passage for the fuel. This leads through the piston 29 into the combustion chamber 25', Fig. 3.

The fuel feed control shown in Fig. 4 is as follows:—63 is a T-shaped shell having a 15 chamber 64. At its top the shell has an air inlet passage 65 to the chamber 64 which is connected by a branch pipe 66 with the base 39 from the outlet 42' of the valve shell 41. This passage 65 is controlled interiorly by 20 a downwardly opening valve 67, suspended by a collar 68 on top of its stem 69.

The shell 63 at its lower end has a passage 70 to the chamber 64 which is connected by a pipe 71 with the fuel inlet passage 62 in 25 the piston 29. This passage 70 is controlled by a valve 72 opening downwardly, but normally closed by a spring 73.

The leg of the shell 63 has a passage 74 30 to the chamber 64, which connects with a suitable source of liquid fuel (not shown) under pressure. The passage 74 is controlled by an inwardly opening valve 75, held to its seat by a spring 76.

The piston 29 is provided with water cooling passages 77 (Fig. 5) connected at their 35 top by a passage 78 (Fig. 3). These passages are connected with the inlet 27 of the water chamber 26 in the mortar 6, by a flexible hose 79, and the water system discharges 40 through an outlet 80 from the piston passages.

In Fig. 2, 81 is a contact spring of the ignition system, and 82 is the other contact, the former being secured to the frame column 45 2 and suitably insulated, and the latter being carried by the mortar 6.

83, Fig. 5 is a set screw adapted to be inserted through a hole in the mortar and to engage the piston 29 when said piston is 50 to be locked to the mortar preparatory to turning the mortar outwardly as heretofore mentioned whereby said piston is prevented from dropping out after it is reversed by the swinging-mortar from the support on the frame base.

55 The operation of my ore-stamp-mill is as follows:

The ore and the necessary water are supplied to the hopper 11, and thence pass down 60 through bores of the sleeve 9, fixed stamp 8 and its die 10 into the mortar 6.

Compressed air from a suitable source is admitted to the inlet 42 of the valve shell 41; also to the inlet connection 49 of the plug 65 48 in the bottom of the mortar; and also to

the air passage 57 in the piston 29, with the following effects, namely:—The air to the inlet 42 passes the valve 43 and out through outlet 42' and hose 39 into the air passage 70

chamber 33 under the lower head of the piston-valve 34, forces said valve up. This movement of the piston-valve 34, connects

the air passages 57 and 60 through the ports 58 and 59, so that the air admitted to the 75

passage 57 now enters the combustion chamber 25'. At the same time the compressed air from the outlet 42' of the valve-shell 41, passes through the branch pipe 66 from the 80

hose 39 and enters the upper passage 65 of the fuel-injector shell 63. This air passing 85

the valve 67 enters the chamber 64 of said shell 63, and forces the charge of liquid fuel which had entered said chamber through the fuel side passage 74, out of said chamber, 90

through the valved lower passage 70, and pipe 71 into the fuel passage 62 in the piston 29, from which passage the fuel is delivered 95

into the combustion chamber 25', wherein it mixes with the air delivered through the 100

passage 60. The pressure of this air admitted through passage 60 to the combustion chamber 25' causes the mortar 6 to rise on 105

its guides 5, and this initial movement of the mortar closes the ignition circuit at the contacts 81 and 82, whereby by means of the 110

spark plug 30, the explosive mixture in the combustion chamber is fired, thereby driving the mortar 6 upward with a heavy blow, and crushing its contents against the die 10 of 115

the fixed stamp 8.

This blow causes the weight 46 in the bore 45 of the mortar to rise thereby through the collar 54 of the upper stem 53, lifting the 120

valve 52 and exposing the port 50 to the passage of the compressed air which had initially been admitted to the inlet connection 49 of the plug 48. This air now passes out 125

through passage 51 in the plug 48 and through the hose 40 and passage 38 in the piston 29, and enters the valve chamber 33

above the upper head of the piston valve 29. The piston valve 29, is thus forced down, and the burnt gases exhaust through the passage 130

61. The mortar drops and by the contact 115 of the valve stems 55 and 44 with the base 1 and mortar 6 respectively, the initial positions are restored for a repetition of the operation.

When it is desired to swing the operative 120 parts of the mill outwardly from the frame as heretofore mentioned, the set screw 83 is inserted to lock the piston 29 to the mortar.

Then compressed air is admitted to the space above the piston 29, to lift the 125

mortar with its locked piston clear of the base and to bring it up near the stamp, and while in this lifted position the pin 5' is

passed into the mortar and engages the socket 5" in the guide 5, whereby the mor- 130

tar is held elevated. Then the suspension sleeve 9 is unscrewed from the stamp 8, which thus is dropped onto the mortar. Then one of the guides 5 is removed and 5 the whole mortar, with its stamp and piston is turned outward on the other guide 5 as an axis, Fig. 6. Then finally the stamp may be hoisted out by any suitable lifting means.

10 Although I have herein described and illustrated in detail the automatic control of what may be considered an explosive engine as the prime mover of my stamp-mill, I have done so merely to disclose an operative 15 device, but it is not my intention herein to claim such details, *per se* as they pertain more properly to the class of internal combustion engines. It is my intention, however, herein to claim such general features 20 of the prime-mover as may legitimately enter into combination with and form an intimate part of the mill proper, by reason of their positional relation thereto, resulting in advantages which I shall now set forth.

25 By making the engine bore or cylinder 25 directly in the mortar, I am enabled to get an evenly distributed blow close to the ore-crushing impact surfaces of mortar and stamp, thus avoiding undue strain on the 30 guides 5, which prolongs the life of the mill.

I also dispense with many otherwise necessary pipes, rods and other connections, liable to work loose and requiring expense in construction and maintenance.

35 Also by having the engine below I avoid any oil getting into the mortar, the presence of which is detrimental to the treatment of ores which are being amalgamated.

Another advantage of having the engine 40 practically a part of the mortar is that the heat developed by the engine is transmitted to the amalgamating minerals within the mortar, which aids in the process of amalgamation, and at the same time, this heat 45 lessens the liability of breakage of the mortar from the jar.

The piston can be removed from the mortar bore easily, when the mortar is swung outward. This movement of the mortar is 50 practicable by reason of the engine structure forming a part of it, so that all interior parts of the mortar may be reached, and the amalgam removed.

By casting the chamber 18 in the mortar 55 outside the screen, no material or slush can be thrown out on the engine parts.

I claim:

1. An ore stamp mill comprising a frame; guides fitted to the frame; a mortar fitted 60 upon said guides for reciprocative movement, and adapted by the removal of one of said guides to be turned outwardly from the frame upon the other of said guides as an axis; a fixed stamp carried by the frame;

and means for reciprocating the mortar to 65 crush the ore against the stamp.

2. An ore-stamp-mill comprising a frame; a mortar mounted in the frame for reciprocative movement; a pivotal connection between the mortar and frame adapting the 70 mortar to be turned outward from the frame; a stamp detachably carried by the frame and adapted to be lowered into the mortar to be turned outwardly therewith; and means for reciprocating the mortar to crush the ore 75 against the stamp when the latter is secured to the frame.

3. An ore-stamp-mill comprising a frame; guides fitted to the frame; a mortar fitted upon said guides for reciprocative movement 80 and adapted by the removal of one of said guides to be turned outwardly from the frame, upon the other of said guides as an axis; a stamp detachably carried by the frame and adapted to be lowered into the 85 mortar to be turned outwardly therewith; and means for reciprocating the mortar to crush the ore against the stamp when the latter is secured to the frame.

4. An ore-stamp mill comprising a frame 90 composed of a base, a column at one side and an overhung top surmounting the column; a pair of vertical guides fitted through the overhung top and passing down into the base beyond the sides of the column; a fixed 95 stamp fitted under the frame top and removably suspended therefrom; a mortar fitted upon the guides for vertically reciprocative movement and adapted upon the removal of one of said guides to be turned 100 outwardly from the frame upon the other guide; and means for reciprocating the mortar to crush the ore against the stamp.

5. An ore-stamp-mill comprising a frame composed of a base, a column and a top; a 105 pair of vertical guides fitted into the top and base of the frame; a suspending member through the frame top; a stamp removably suspended by said member and abutting under the frame top; a mortar fitted upon the guides for vertical reciprocative movement and adapted upon the removal of one of said guides to be turned outwardly 110 from the frame upon the other guide; and means for reciprocating the mortar to crush 115 the ore against the stamp.

6. An ore-stamp mill comprising a frame composed of a base, a column and a top; a pair of vertical guides fitted into the top and base of the frame; a longitudinally 120 bored suspending member fitted through the frame top; a longitudinally bored stamp removably suspended by said member and abutting under the frame top; a feed hopper carried by said member and adapted to 125 supply the ore therethrough and through the bored stamp; a mortar fitted upon the guides for vertical reciprocative movement

and adapted upon the removal of one of said guides to be turned outwardly from the frame upon the other guide; and means for reciprocating the mortar to crush the ore against the stamp.

7. An ore - stamp - mill comprising a frame; a fixed stamp carried thereby; a mortar mounted in the frame for vertical reciprocative movement to crush the ore against the stamp; a screen carried by the mortar and spaced from the stamp; said mortar having a closed chamber outside the screen with a discharge passage leading from the chamber and down through the mortar; and means for reciprocating the mortar.

8. An ore-stamp mill comprising a frame; a fixed stamp carried thereby; a mortar mounted in the frame for vertical reciprocative movement to crush the ore against the stamp; a screen carried by the mortar and spaced from the stamp; a funnel shaped guard member carried by the mortar and lying in the top of the space between the screen and stamp adapted to direct the splashed pulp against the screen; and means for reciprocating the mortar.

9. An ore - stamp - mill comprising a frame; vertical guides in the frame; a fixed stamp carried by the frame; a mortar mounted on the frame guides for vertical reciprocative movement to crush the ore against the stamp; a screen carried by the mortar and spaced from the stamp, said mortar having a chamber outside the screen and a discharge passage from said chamber; a funnel shaped guard member carried by the mortar and lying in the top of the space between the screen and stamp adapted to direct the splashed pulp against the screen; an inverted funnel guard carried

by the mortar and lying above the first named guard to protect the sliding surfaces of the mortar from the splash; and means for reciprocating the mortar.

45

10. An ore - stamp - mill comprising a frame; a fixed stamp carried by the frame; a mortar mounted in the frame for reciprocative movement to crush the ore against the stamp, said mortar having a bore leading upwardly from its bottom and closed at its upper end; a piston carried by the frame and fitting the base bore of the mortar; and means for supplying an expansive fluid medium to the space between the top of the bore and the top of the piston, to drive the mortar upwardly.

50

11. An ore - stamp - mill comprising a frame; a mortar mounted in the frame for vertical reciprocative movement; a pivotal connection between the frame and the mortar adapting said mortar to be swung outward from the frame; a stationary stamp detachably connected with the frame and adapted to be lowered into the mortar when the latter is turned outward, said mortar having a bore leading upwardly from its bottom and closed at its upper end; a piston fitting in the mortar bore and resting freely on the frame whereby said piston accompanies the mortar when turned outward; and means for supplying an expansive fluid medium to the space between the top of the bore and the top of the piston, to drive the mortar upward.

55

In testimony whereof I have signed my name to this specification in the presence of two subscribing witnesses.

JAMES W. VANMETER.
